UNITED STATES PATENT OFFICE.

GEORGE POIRIER, OF GROSVENOR-DALE, CONNECTICUT, ASSIGNOR TO DRAPER CORPORATION, OF HOPEDALE, MASSACHUSETTS, A CORPORATION OF MAINE.

AUTOMATIC FILLING REPLENISHING LOOM.

Application filed November 27, 1925. Serial No. 71,545.

This invention relates to automatic filling replenishing looms and is more particularly directed to improvements in the filling batteries of such looms.

It is now the common practice to support a number of filling carriers or bobbins supplied with filling in a hopper for transfer to the shuttle on call for replenishment of filling by a feeler or weft fork mechanism. In filling batteries of the rotary type, the heads of the bobbins or filling carriers are supported in recesses formed in a rotary disk, while the end portions are usually maintained in a complementary disk spaced some distance therefrom, and in order to maintain the filling carriers in the hopper, the disk supporting the heads of the bobbins is usually provided with a flange which overlies the bobbin heads. When the filling carriers or bobbins, however, reach transferring position, a throat or passageway is provided through which the filling carrier or bobbin is thrust by a transference forming part of a transferring mechanism. When the bobbins are in transferring position opposite the throat, it is desirable that they be retained in their hopper supporting position above the throat until the transferring mechanism acts to thrust the filling carrier into the shuttle.

One of the objects of the present invention, therefore, consists in simple and effective means for insuring proper retention of the filling carrier or bobbin in the hopper when in transferring position until the transferring mechanism is brought into action, and thereupon to remove the means or instrumentality from the path of the bobbin to permit it to pass into the shuttle.

In accordance with the present position, a guide forward of the throat serves to direct the incoming filling carrier or bobbin into the shuttle, and cooperating with the guide is a sliding member which is withdrawn forwardly from the path of the filling carrier or bobbin when the transferring mechanism is brought into action. More specifically stated, the present invention comprises a sliding pin or slide member, the end of which normally projects into the bobbin throat during normal weaving operation and is so connected or articulated with the replenishing mechanism that on the transferring operation of such mecha-

nism, the sliding member or pin is withdrawn frontwardly out of the path of the incoming bobbin or filling carrier.

The invention and new combination of parts will best be made clear from the following description and the accompanying drawings showing one good form thereof.

In the drawings:

Fig. 1 is an end elevation, partly in section, showing the battery mechanism of a loom provided with the present invention, the transferring mechanism being in normal inoperative position;

Fig. 2 is a similar section elevation showing the transfer mechanism thrusting a bobbin from the hopper to the shuttle, and containing the present invention; and

Fig. 3 is a perspective view showing the parts in normal position during weaving.

The hopper for containing the filling carriers or bobbins supplied with filling may be of usual character and comprises a stand 1 mounted upon the loom frame and supporting a pin or dead shaft 2 on which is rotatably mounted the hopper head 3 provided with a number of recesses 4 adapted to hold the head portions of filling carriers or bobbins. The stand 1 is provided with a flange 5 which is preferably widened at its back lower portion at 6 to insure the retention of the filling carriers or bobbins in the hopper as it is periodically rotated. The means for rotating the hopper to bring the filling carriers or bobbins successively to transferring position may be of any usual type and is not herein shown because it forms no part of the present invention.

There is usually associated with the rotary head 2 an opposite head for retaining the tip portions of the bobbins 7, and while such tip supporting portion of the hopper may be desirable in some cases, it is not always necessary and is not herein shown because it forms no essential part of the present invention.

Extending from the hopper stand 1 is the pin or dead shaft 8 on which is mounted the transference 9 having a head portion 10 for engaging the bobbins near the heads thereof during the downward movement of the transference, as usual. The transference is normally held in its normal inoperative position by a spring 11, and the hub portion

of the transferrer is provided with a downwardly extending operating arm 12 to which is pivotally connected at 13 the usual dog 14 which is under the control of means actuated by feeler or filling fork mechanism, such as the arm 15, to raise the dog into position for engagement by a bunter 16 carried by the lay 17 when filling replenishment is to be effected. The parts thus far described may be of usual character and operate in the usual manner to effect the transfer of a filling carrier or bobbin from the hopper to the shuttle during transfer, as more clearly indicated in Fig. 2, it being understood that the shuttle 18 is provided with a bottom opening 19 from which the filling carrier or bobbin previously in the shuttle may be ejected.

Secured to the loom frame and extending rearwardly from the front thereof is a fixed arm 20 the rear end portion of which is formed as a bobbin guide 21 and constituting the front wall of the open throat 22 through which the bobbins pass on their way from the hopper to the shuttle, the opposite wall of the throat being formed in the present instance by a fixed abutment 23.

The transferrer 9 is usually provided with a bobbin tip engaging member, such as 24, so that as the bobbin is transferred from the hopper to the shuttle, both ends will usually be engaged by a part connected to the transferrer.

In accordance with the present invention, when a bobbin is in transferring position opposite the throat 22, the head of the bobbin rests against the fixed bobbin guide 21, and a sliding instrumentality is provided which projects beyond the bobbin engaging face of the guide 21 to insure that the bobbin when in transferring position shall not be displaced therefrom or fall into the throat leading from the hopper.

As shown in the present instance of the invention, the sliding member or instrumentality normally extends into the throat 22 beneath the head of the bobbin in transferring position, and is connected with the transferring mechanism to be withdrawn frontwardly when the transferrer thrusts a bobbin from the hopper through the throat into the shuttle.

In the present instance the sliding member is formed as a pin 25 which passes through an opening 26 formed in the guide 21 and constituting a bearing for the rear end portion of the pin 25. The pin 25 extends frontwardly below the transferrer 9 and at its front end portion is pivotally connected at 27 to the transferrer operating arm 12, the construction being such that when the dog 14 is engaged by the bunter 16 on call for replenishment of filling, the transferrer operating arm 12 is moved frontwardly, as indicated in Fig. 2, thereby with-

drawing the pin 25 frontwardly from the throat 22 and out of the path of the incoming filling carrier or bobbin.

During normal weaving operation, the sliding member or pin 25 has its rear end portion 27 extending beyond the bobbin engaging face of the guide 21 below the bobbin head in the hopper when the bobbin is in transferring position. On call for replenishment of filling, however, as the transferrer is actuated to transfer a bobbin or filling carrier from the hopper, the sliding member or pin 25 is withdrawn frontwardly out of the throat 22 and frontward of the bobbin engaging face of the guide 21, thereby opening the throat for the free passage of the filling carrier or bobbin from the hopper to the shuttle.

Within the broader aspects of the invention, the pin 25 may be variously contrived, and so also may the bearing for the pin or sliding member 25, but the described construction provides a very simple and yet an effective means for retaining the bobbin in the hopper when it is in transferring position opposite the throat 22 and for withdrawing it therefrom upon actuation of the transferrer.

What is claimed is:

1. In a filling replenishing loom, the combination of a hopper for supporting filling carriers, a bobbin guide and abutment constituting a throat for the passage of a filling carrier during transfer, a guard mounted for sliding movement extending rearwardly from the rear surface of the bobbin guide in a direction transversely across the throat below a filling carrier when in replenishing position to prevent movement of a filling carrier through the throat, and means for connecting the sliding guard with the transferring mechanism to cause the guard to slide frontwardly from its obstructing position in the throat and permit the passage of a filling carrier on replenishment of filling.

2. In an automatic filling replenishing loom comprising a hopper having a throat for the passage of a filling carrier and a transferring mechanism, a guard constituted as a slide which extends rearwardly across the throat beneath a bobbin when in transferring position to obstruct the throat passage and prevent movement of a filling carrier or bobbin through the throat, and connections between the slide and transferring mechanism operable by the latter to withdraw the slide frontwardly out of the path of the filling carrier as the latter is transferred.

3. In a filling replenishing loom, the combination of a hopper, a throat leading from the hopper and constituted as a front guide and rear abutment, a transferring mechanism, a pin extending from the rear face of the front guide in a direction transversely

of the throat beneath a filling carrier when in transferring position to prevent downward movement of a filling carrier, and connections between the pin and transferring mechanism for retracting the pin frontwardly out of the throat to clear the throat for the passage of a filling carrier on operation of the transferring mechanism.

4. In a filling replenishing loom, the combination of a hopper, a throat leading from the hopper and constituted as a front guide and rear abutment, a transferring mechanism, a guard formed as a sliding pin extending from the rear face of the front guide into the throat beneath a filling carrier when in transferring position to prevent downward movement of the filling carrier, and connections between the guard and transferring mechanism for retracting the guard frontwardly relative to the rear face of the guide to clear the throat for the passage of a filling carrier on operation of the transferring mechanism.

5. In a filling replenishing loom, the combination of a hopper, a throat leading from the hopper and constituted as a front guide and rear abutment, a transferring mechanism, a sliding guard extending from the rear face of the front guide into and transversely across the throat beneath a filling carrier when in transferring position to prevent downward movement of a filling carrier, and connections between the guard and transferring mechanism for sliding the guard frontwardly out of the throat to clear the throat for the passage of a filling carrier on operation of the transferring mechanism and said connections acting to project the guard transversely across the throat as the transferring mechanism returns to its inoperative position.

6. In an automatic filling replenishing loom, the combination of a hopper having a

fixed front bobbin guide against which a bobbin rests when in transferring position, a pin mounted for sliding movement relative to the bobbin guide and normally extending beyond the guiding face of the bobbin guide beneath the head of a bobbin when in transferring position, transferring mechanism, and connections between the sliding pin and transferring mechanism for withdrawing the pin frontwardly as a bobbin is transferred and acting to restore the pin to its original position after the transfer has been effected.

7. In an automatic filling replenishing loom, the combination of a hopper having a fixed bobbin guide against which the head of a bobbin rests when in replenishing position, a sliding pin extending through a bearing at the bobbin guide and normally projecting rearwardly beyond the guiding face of the guide below the head of the bobbin, a transerrer having an operating arm extending downwardly to which the front end of the sliding pin is connected to cause the sliding pin to be withdrawn from the path of the bobbin as the transerrer is operated to effect the transfer.

8. In an automatic filling replenishing loom, the combination of transferring mechanism, a hopper having a front bobbin guide forming the front wall of a throat, a sliding pin passing through a bearing carried by the bobbin guide and having its front end portion connected to the transferring mechanism to cause the sliding pin to be withdrawn frontwardly out of the throat as a bobbin is thrust through the throat by the transferring mechanism.

In testimony whereof, I have signed my name to this specification.

GEORGE X POIRRIER.
